UNITED STATES PATENT OFFICE.

BERT CARLISLE, OF SANTA ANA, CALIFORNIA.

HEADLIGHT-LENS.

1,316,829.

Specification of Letters Patent. Patented Sept. 23, 1919.

Application filed March 20, 1919. Serial No. 285,375.

To all whom it may concern:

Be it known that I, BERT CARLISLE, a citizen of the United States, residing at Santa Ana, in the county of Orange and State 5 of California, have invented new and useful Improvements in Headlight-Lenses, of which the following is a specification.

My invention relates to headlight lenses and consists of the novel features herein 10 shown, described and claimed.

My object is to make a supplemental lens which may be used in connection with any of the ordinary main lenses and which will satisfactorily perform the operation of dimming and diffusing the light and eliminate 15 the objectionable glare.

Figure 1 is a vertical longitudinal diametrical sectional detail of a headlight with a supplemental lens embodying the principles of my invention in position for use.

Fig. 2 is a front elevation upon a reduced scale of the supplemental lens.

The headlight construction 1 may be any of the usual constructions having a reflector 25 2 and an electric lamp 3. As shown, the main lens 4 is mounted from the inside in a finishing ring and cap 5 having supporting clips 6 extending inwardly, and a cushion ring 7 at the rear side of the glass in position to the bearing edge 8, said bearing 30 edge 8 being at the front side of the glass.

My supplemental lens 9 is circular in plan and substantially the same size as the main lens 4. The supplemental lens has a rim 35 portion 10 having a flat front face 11 fitting the flat rear face of the main lens 4, an edge 12 fitting in the clips 6 between the cushion 7 and the main lens, the curved face 13 at the rear side and opposite the 40 flat face 11, the reversely curved face 14 extending backwardly and inwardly from the face 13, the rounded face 15 extending inwardly and backwardly from the face 14, the flat face 16 extending inwardly from 45 the rounded face 15 substantially parallel with the main lens, or in a transverse plane, and the curved front face 17 extending from the inner edge of the flat face 11 to the inner edge 18 of the flat face 16, there being 50 a circular opening 19 bounded by the inner edge 18. The inner edge 18 is concentric to the lamp 3 and nearly half way between the lamp filament and the main lens 4, the

inner edge of the flat face 11 is concentric to the inner edge 18, and the inner face 5 17 is nearly parallel with the reflector 2 and concentric to the reflector. In cross section the glass is thickened on the line 20 all the way around and on the line 21. The face 17 is concave, and the face 15 6 joined to the faces 14 and 16 makes a convexity, and the face 13 is concave.

In the practical operation the rays of light reflected by the outer part of the reflector 2 ordinarily join with the light coming straight from the lamp and produce a concentration of light which is glaring and blinding. In the use of my supplemental lens these rays of light passing from the outer part of the reflector will strike the 70 faces 13, 14, 15 and 16 and be interrupted and diffused from the face 17. The supplemental lens will fill all the requirements of a dimmer, and at the same time present a better appearance.

Various changes may be made without departing from the spirit of my invention as 75 claimed.

I claim:

1. As an article of manufacture a supplemental lens having a central opening and a concavo-convex portion around the central opening with the concave side to the front and the curvature of the convex face being greater than the curvature of the concave 85 face, and there being a portion extending outwardly from the concavo-convex portion and adapted to fit against a main lens, the central opening in the supplemental lens allowing the rays to pass freely to the central portion of the main lens.

2. As an article of manufacture a supplemental lens having a central opening and a concavo-convex portion around the central opening with the concave side to 95 the front and the curvature of the convex face being greater than the curvature of the concave face, and there being a portion extending outwardly from the concavo-convex portion and adapted to fit against a 100 main lens, the bearing portion having a concave rear face.

In testimony whereof I have signed my name to this specification.

BERT CARLISLE.
